UNITED STATES PATENT OFFICE.

GEORGE A. HILTON, OF IRVINGTON, NEW JERSEY, ASSIGNOR OF ONE-HALF TO LOUIS E. HECHT, OF IRVINGTON, NEW JERSEY.

HANGER FOR BRUSHES.

1,308,074.

Specification of Letters Patent.

Patented July 1, 1919.

Application filed March 18, 1919. Serial No. 283,316.

To all whom it may concern:

Be it known that I, **GEORGE A. HILTON**, a citizen of the United States, and a resident of Irvington, county of Essex, and State of New Jersey, have invented certain new and useful Improvements in Hangers for Brushes, of which the following is a specification.

My invention relates to hangers for brushes such as paint brushes and the like, adapted to be used for suspending the brushes in a vessel containing water, oil or similar fluids for keeping the bristles in condition, in such manner that the bristles are permitted to hang substantially straight downwardly, and are held out of contact with the walls of the vessel.

An object of the invention is the provision of a hanger which can be constructed separately from the brush, involving no change or additional steps in the process of brush manufacture, and can be applied to substantially any form of brush, either at the time of manufacture, or can be applied thereafter by master painters, or others, to brushes which were not equipped with hangers at the time of manufacture.

Another object is the provision of novel means for holding the hanger hook in retracted position where it is out of the way when not wanted, but can be readily turned to position for use.

Other objects of the invention will appear in connection with the following description, and with the foregoing and related object in view, my invention consists in the elements, combinations and features of construction herein set forth and claimed.

In the accompanying drawings forming a part of this specification, and wherein the same reference numerals are made use of uniformly to designate the same parts throughout, Figure 1 is a fragmentary sectional view of a pot with one form of brush equipped with a hanger in accordance with my invention, and suspended therein, the retracted position of the hanger being shown in dotted lines. Fig. 2 is a plan view of the brush hanger as shown in Fig. 1, the hanger being shown in retracted position. Fig. 3 is a fragmentary perspective view of a flat brush equipped with a hanger in accordance with my invention. Fig. 4 is a sectional view taken on the line 4-4 of Fig. 3, and Fig. 5 is a plan view showing several brushes

suspended by my improved hangers about the walls of a pot or vessel.

In order that a hanger may be a practical success, a number of requirements are of importance. It must be permanently attached to the brush, so as to be readily available at the point where wanted for use. It must be retractable to a position where it is out of the way and there securely held or retained. It should not require any change in the brush or in its mode of manufacture. It should not be so constructed that it will readily clog with paint or be difficult to bring into operative position when wanted, and a hanger in accordance with the present invention fulfills all these requirements, and has still other features of advantage.

Two forms are shown for purpose of illustration, and for making the invention clearly understood: one for the ordinary flat paint brush or the like, and one for the round brush usually made use of for a varnish brush. The former is shown in Figs. 3 and 4. It comprises essentially a body member 10 adapted to be secured to the brush and a hook member 11 pivoted to the body member at substantially the end thereof, which is to be placed adjacent to the outer end of the brush head 12. In the form shown, the body member 10 is formed of sheet metal, and made up at its middle portion in substantially the form of a narrow, substantially box shaped member 13 comprising an upper or top wall portion 14 and side walls 15, 15. The side walls are provided with outwardly directed extensions or flanges 16, 16 of a form adapted for fitting down on the brush head, and are secured thereon by suitable means as by small nails or brads 17, 17, driven through openings provided therefor in such flanges or extensions.

The side walls 15, 15 are preferably of substantially triangular form, so that the outer end of the upper wall 14 of the portion 13 comes down substantially close to the brush head, while the inner end thereof is elevated somewhat with respect to the brush head. At the outer end of the body member 10, means are provided for pivotally receiving a hook member, and in the form shown, the top portion 14 is made somewhat longer than the sides and brought back on itself, so as to provide substantially a transversely extending bore 18 at its extreme end for the reception of the hook member.

The hook shown has the form of a double hook. The hook member is designated generally by the reference numeral 11, and comprises two hooks 19, 19 which may be formed 5 of wire or the like material, and are joined together by the transversely extending portion 20, which is received in the bore 18 provided therefor, so that the hook member may turn therein as upon the pivot. In order 10 that the hook ends 21, 21 of the hooks 19, 19 may extend outwardly or outwardly and downwardly when in use for suspending the brush from a suitable support, it results that they are turned upwardly when brought 15 back into retracted position, as shown in Fig. 3, and it is for this reason that the rear portion of the box shaped part 13 is made higher than the outer end portion thereof, and when so formed, it serves to retain the 20 hook member in retracted position, and to keep the hooks substantially out of the way. In order to obtain a positive holding connection for the hooks, the box shaped member 13 may be somewhat thicker at its top, 25 or it may be formed with laterally extending ribs or flanges 22, 22 along the upper side portions thereof, and when the hooks 19, 19 have a slight tension toward one another and are sprung thereon, these ribs or flanges 30 22, 22 serve to retain the hooks in retracted position, as will be plain from the showing in Fig. 4.

The form of the hanger for round brushes shown in Figs. 1 and 2, differs from that 35 shown in Fig. 3 for flat brushes, in that, instead of providing the side parts with laterally extending portions for fastening in position on the brush head, the side members 15, 15 are provided with rearwardly extending 40 portions 24, 24 by which the body member 10' is secured to the handle 25 at substantially the base thereof adjacent to the brush head.

The operation of a hanger in accordance 45 with my invention, will be clear from the foregoing. The device is made up separately and attached to a brush. When not wanted for suspending a brush, the hook is simply turned backwardly on its pivotal 50 support in which position it is positively held in place until wanted for use, and when

the brush is to be hung up, the hook member is readily grasped by the painter and turned upwardly and outwardly on its pivot, and may be used for suspending the brush upon 55 a suitable support as upon the side wall of a pot or vessel containing water, oil or the like, 26 as indicated in Fig. 1. A number of brushes may be hung in a vessel and will extend radially inwardly from the side walls 60 thereof, as shown in Fig. 5, so that in a vessel of moderate size, a considerable number of brushes may be hung. As already 65 stated, the invention comprises the hanger as a separate article of manufacture, and also comprises hangers in combination with the brush, the device being adapted to be manufactured and sold separately for attachment to brushes already completed or in use, or to be applied to the brush at the time 70 of original manufacture.

Modifications and changes may be resorted to within the scope of my claims, as, for example, the body member may be of other forms, a single hook may be used, etc. 75

I claim:

1. A hanger comprising a body member having a substantially triangular side and adapted to be secured to a brush head with the base of the triangular side directed inwardly, and a hook member pivoted thereto at substantially the outer end thereof, and adapted to be folded on its pivot with its hook directed upwardly and held in such retracted position in contact with the side 85 of the body member.

2. A hanger comprising a sheet metal body portion with substantially triangular sides and having a rib at the top of each side wall, a hook made of a single piece of 90 wire having a transverse portion hinged to the small end of the triangular body portion and having two hooks adapted to be swung outward to suspending position or inward to retracted position, the hook ends having 95 a slight tension toward one another so that they can be sprung under the ribs to hold the hook in retracted position.

In testimony that I claim the foregoing, I have hereto set my hand, this 11th day of 100 March, 1919.

GEORGE A. HILTON.
